CONCEALABLE SHELTER BUILDING

Benjamin Berman, Brooklyn, N. Y.

Application March 21, 1951, Serial No. 216,819

7 Claims. (Cl. 20—1)

This invention relates to a concealable building, and, more particularly, to a building adapted to be concealed beneath the ground level in the event of an aerial or artillery bombardment, or of a windstorm such as a hurricane or tornado.

One object of the invention is the provision of a structure for normally supporting a building above the ground level but which is capable of lowering the building completely below the ground level.

Another object of the invention is the provision of means operative to provide such a building with water, sewage and electrical facilities in either of its positions.

Still another object of the invention is the provision of means for covering the building when the latter is in its underground position, the location of the building thus being camouflaged.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of the building support structure.

Fig. 2 is a sectional view of the structure on line 2—2 of Fig. 1, with a building being indicated in dot-dash lines.

Fig. 3 is a fragmentary sectional view on line 3—3 of Fig. 1, and illustrates the sewage connections for the building.

Fig. 4 is a fragmentary sectional view on line 4—4 of Fig. 1 and illustrates the water supply for the building.

Fig. 5 is an enlarged fragmentary sectional view illustrating the valve means for the water supply.

Fig. 6 is an enlarged sectional view on line 6—6 of Fig. 5.

Fig. 7 is a fragmentary sectional enlargement of a portion of Fig. 5.

Fig. 8 is a fragmentary enlarged sectional view of the means for concealing the building.

Fig. 9 is an enlarged fragmentary perspective view of a portion of Fig. 8.

Fig. 10 is the wiring diagram of the invention.

Referring now to the drawings, the means of the invention is adapted normally to support a suitable building 10 at ground level and in the event of an emergency to support the building below ground level. As shown, the building 10 is fixed on a rectangular frame 11 which is made up of rectilinear and diagonal beams 12 which preferably are of the steel I type. Frame 11 is supported by four worms or screws 13 which extend downward into a pit 14 having concrete walls 15. At their upper ends the worms 13 are journaled in brackets 16 embedded in the walls 15 and at their lower ends are journaled in suitable bearing boxes 17. The screws, therefore, are adapted to rotate without moving axially. Each worm 13 is located in a vertical groove or channel 18 at the center of one of the walls 15 and is threaded through a block 20 secured centrally to a side of frame 11 and projecting into said channel. It will be understood, however, that any number of worms may be provided.

The construction thus far described is such that rotating the worms 13 in a common direction will raise or lower the frame 11 and the building supported thereon. Thus, said building can be positioned above the ground level or down in pit 14 entirely below ground level.

If desired, automatically removable supports may be provided for frame 11 when the latter is in its upper position although the utilization of the worms 13 obviates the need therefor.

5 In order to rotate the worms 13, a sprocket wheel 21 is fixed on each just above the bearing box 17, said sprockets being engaged by an endless chain 22 which is driven by a sprocket 23 on the shaft of an electric motor 24 mounted in the base of pit 14. Motor 24 preferably is of the type adapted to rotate in either direction under control of suitable switching means, so that the same may be utilized for both raising and lowering frame 11. Of course, the chain drive may be replaced by any other type if such is desired.

In order to provide an electric supply to building 10 in either of its positions, a cable 25 extends downward from the building into pit 14 and at the base of the latter is wound on a spring loaded drum 26 adapted to wind up the cable as building 10 is lowered. Drum 26 is pivotally supported in brackets 27 and the end of cable 25 is electrically connected in any suitable manner with a cable 28 leading out of pit 14 to a source of supply.

In order to provide water supply for building 10 in either of its positions, the following means is provided:

Secured beneath frame 11 near one corner thereof is a box-like unit 30 having rounded upper and lower outer edges 31, see also Fig. 4. Mounted within unit 30 and projecting vertically therefrom to a suitable cut-off valve 39 is a supply pipe 32 which by an elbow 33 is connected with a second pipe 34 opening out of the outer face of the unit. Preferably the end of pipe 34 is flush with the outer face of said unit and is concavely ground to form a seat 35, see also Fig. 5. The water supply main 36 extends into the wall 15 adjacent unit 30 at the level of said unit when frame 11 is in its upper position and is provided with an extension 37 which extends downward and into wall 15 at a point suitable for cooperation with said unit when the frame is in its lower position. The ends of mains 36 and 37 are embedded in the walls 15 and each has secured thereon, see also Figs. 6 and 7, a tube 38 which extends out of wall 15 in alignment with the end of pipe 34 of unit 30. Slidably mounted in the free end of tube 38 is a hollow piston 40 whose nose 41 extends beyond the end of the tube and is convexly curved to fit the seat 35 of pipe 36. A suitably sized opening 42 is provided in nose 41. The base of piston 41 is provided with a plurality of openings 43 and at its center has fixed therein the reduced end of a rod 44. Rod 44 extends interiorly of an internal annular ring or ridge 45 of tube 38 and has fixed on its end a circular plate 46. A coiled spring 49 tensions plate 46 against ring 45 and effectively prevents a flow of water from main 36 or 37 into piston 40.

In order to make the plate 46 smaller and the openings 43 in piston 40 larger to allow a maximum flow of water from pipe 36 or 37 into piston 40 when said plate is moved away from ring 45, said ring tapers in diametral thickness as indicated at 47. Thus, the opening surrounded by the ring increases in diameter as it extends toward piston 40.

The construction is such that normally the piston 40 is in its projected position with the plate 46 blocking a flow of water from main 36 or 37. However, as frame 11 is raised or lowered, the rounded upper or lower edge 31 engages the curved nose 41 of piston 40 and cams the latter into tube 38. This frees plate 46 from ring 45 and a flow of water into piston 40 is permitted. Immediately following the camming of piston 40, the rounded nose thereof snaps into the seat 35 of pipe 34 and a water supply connection is completed. It is believed obvious that the connection is equally effective for either position of building 10. Valve 39 is, of course, utilized to prevent a back flow of water from building 10 while the same is being raised or lowered.

In order to provide sewage facilities for building 10 a waste pipe 48 is connected to a suitable sewer or cesspool and extends into a wall 15 at two vertically spaced positions. The two branches of waste pipe 48 are provided with connecting valve means identical with those

provided for water mains 36 and 37 except in size. These means, therefore, need not be fully illustrated or re-described. However, the portions thereof shown in Figs. 2 and 4 are given the same reference numerals as hereinabove with a prime added.

It is desired that when building 10 is positioned entirely within pit 14 that the latter be covered to conceal or camouflage the presence of the building. Referring to Figs. 1, 2, 8 and 9, there is provided a sliding cover 50 which comprises a steel plate 51 supported on side beams 52 and cross members 53. Normally cover 50 is located at one side of pit 14 in a flat concrete casing 54 adapted to conceal and protect the same. The side beams 52 preferably are steel C-girders having in their lower flanges longitudinal grooves 55. Embedded in the top of the side walls 15 are a plurality of cups or retainers 56 each having journalably mounted therein a ball bearing 57 adapted to the groove 55. Thus cover 50 rides on the ball bearings 57 which not only facilitate sliding of the cover but also, by engaging in the grooves 55, guide the movement of the cover.

In order to move cover 50 each side beam 52 thereof has secured to its upright portion a rack bar 58 which is engaged by a gear 60 on a shaft 61 which is suitably journaled in the base of casing 54. Shaft 61 is, in effect, an extension of the drive shaft of an electric motor 62 mounted in a compartment 63 at one side of casing 54. Preferably, a removable cover 64 is provided for compartment 63.

Motor 62 also is of the reversible type and in obvious manner is operable to close and open cover 50.

The electrical connections whereby the building 10 can be lowered or raised and the cover 50 opened or closed merely by throwing a switch will now be described. Referring to Fig. 10, the center terminals of a double pole double throw switch 65 which may be located within building 10 are connected to a suitable source of supply. One pair of side contacts of switch 65 are connected through a lead 66, normally closed contacts 67 and a lead 68, with motor 24 for lowering and raising frame 11. The contacts 67 are suitably located in pit 14 so as to be opened when frame 11 reaches its lowermost position. Thus closure of switch 65 on the side under discussion effects lowering of frame 11 into pit 14, which lowering is halted by the opening of contacts 67. The other pair of side contacts of switch 65 are connected with motor 24 in the reverse direction through a lead 70, normally closed contacts 71 and lead 72. Contacts 71 are located in pit 14 in position to be opened when frame 11 reaches its uppermost position.

The construction thus far described is such that throwing switch 65 in one direction causes motor 24 to rotate in a direction to lower frame 11 and throwing it in the opposite direction effects raising of the frame. And the frame 11 is automatically stopped in the proper positions.

The side of switch 65 associated with raising frame 11 is connected with cover motor 62 through a lead 73, normally closed contacts 74 and a lead 75 in such manner that said motor is rotated to open cover 50. Contacts 74 are located in casing 54 in position to be opened by cover 50 when the latter reaches open position. Positionably associated with the contacts 74 are a pair of open contacts 76 in the lead 70 utilized in raising frame 11. When cover 50 reaches open position contacts 76 close and allow frame 11 to rise. Thus, the frame cannot be raised until cover 50 is entirely out of the way.

Motor 62 is connected in reverse direction with the side of switch 65 associated with lowering frame 11 through a lead 77, normally open contacts 78, normally closed contacts 80, and lead 81. Closed contacts 80 are positioned to be opened as cover 50 reaches closed position, the motor 62 being stopped thereby. Open contacts 78 are positionably associated with the contacts 67 at the base of pit 14 and are closed by the frame 11 reaching its lower position. Thus, cover 50 does not start to close until frame 11 and building 10 are completely out of the way.

The construction is such that by means of a single switch the building 10 may be raised and lowered and the cover 50 opened and closed in complete safety.

Due to the fact that the several components of the circuit are so well known, no attempt has been made to illustrate them other than diagrammatically. However,

it is to be mentioned that the leads for switch 65 may be included in cable 25.

It is also to be mentioned that cover plate 51 is provided with a plurality of holes 83 for ventilation of pit 14.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. Concealable building construction which includes a walled pit, a horizontal frame mounted in said pit and adapted to support a building, vertical worms on which said frame is supported for up and down movements, driving means for said forms including a reversible electric motor, a sliding cover for said pit, a reversible electric motor for opening and closing said cover, connecting valve means for supply water and separate connecting valve means for sewage facilities to said building when the frame is at the top of the pit and also when the frame is at the bottom of the pit, comprising upper and lower water supply pipes extending into a pit wall, upper and lower waste pipes extending into another pit wall, a box-like unit secured to said frame for association with said waste pipes, another unit for cooperation with the water pipes, a pipe secured in each said unit for cooperation with the associated waste or water pipes, a concave seat in the end of each last said pipe, a tube secured on the end of each waste and each water pipe and projecting into said pit, a piston slidably mounted in each tube and having a rounded nose adapted to a said seat, an opening in said nose, a plurality of openings in the base of the piston, a rod projecting from the base of the piston, a circular plate at the end of said rod, an internal annular ring in said tube, a spring to press said plate against said ring, and rounded upper and lower ends on each said unit to cam the associated said pistons into said tubes to disengage said plates from said rings as the said frame is moved to its upper and lower positions; and circuit means to energize said motors for raising and lowering the frame and for opening and closing the cover, said circuit means being effective to raise said frame only when said cover is completely open, and to close said cover only when said frame is at the bottom of the pit.

2. Concealable building construction which includes a walled pit, a horizontal frame mounted in said pit and adapted to support a building, vertical worms on which said frame is supported for up and down movements, driving means for said worms including a reversible electric motor, a sliding cover for said pit, a reversible electric motor for opening and closing said cover, connecting valve means for supply water and separate connecting valve means for sewage facilities to said building when the frame is at the top of the pit and also when the frame is at the bottom of the pit, and circuit means to energize said motors for raising and lowering the frame and for opening and closing the cover, said circuit means being effective to raise said frame only when said cover is completely open, and to close said cover only when said frame is at the bottom of the pit, and comprising a double pole double throw switch located in the building to energize said motors in reverse directions; normally closed contacts situated to be opened by said frame and said cover as they reach their terminal positions; the opening of said contacts deenergizing the motors; a normally open contact in the cover motor circuit adapted to be closed as said frame reaches its lowest position, and a normally open contact in the frame motor circuit situated to be closed as said cover reaches its fully open position.

3. Concealable building construction which includes a walled pit, a horizontal frame mounted in said pit and adapted to support a building, vertical worms on which said frame is supported for up and down movements, driving means for said worms including a reversible electric motor, a sliding cover for said pit, a reversible electric motor for opening and closing said cover, connecting valve means for supply water and separate connecting valve means for sewage facilities to said building when the frame is at the top of the pit and also when the frame is at the bottom of the pit; comprising upper and lower water supply pipes extending into a pit wall; upper and lower waste pipes extending into another pit wall; a box-

like unit secured to said frame for association with said waste pipes, another unit for cooperation with the water pipes, a pipe secured in each said unit for cooperation with the associated waste or water pipes, a concave seat in the end of each last said pipe, a tube secured on the end of each waste and each water pipe and projecting into said pit, a piston slidably mounted in each tube and having a rounded nose adapted to a said seat, an opening in said nose, a plurality of openings in the base of the piston, a rod projecting from the base of the piston, a circular plate at the end of said rod, an internal annular ring in said tube, a spring to press said plate against said ring, and rounded upper and lower ends on each said unit to cam the associated said pistons into said tubes to disengage said plates from said rings as the said frame is moved to its upper and lower positions; and circuit means to energize said motors for raising and lowering the frame and for opening and closing the cover, said circuit means being effective to raise said frame only when said cover is completely open, and to close said cover only when said frame is at the bottom of the pit, and comprising a double pole double throw switch located in the building to energize said motors in reverse directions, normally closed contacts situated to be opened by said frame and said cover as they reach their terminal positions, the opening of said contacts deenergizing the motors, a normally open contact in the cover motor circuit adapted to be closed as said frame reaches its lowest position, and a normally open contact in the frame motor circuit situated to be closed as said cover reaches its fully open position.

4. Concealable building construction which includes a walled pit, a horizontal frame mounted in said pit and adapted to support a building, vertical worms on which said frame is supported for up and down movements, driving means for said worms including a reversible electric motor, a sliding cover for said pit, side beams for said cover having each a bottom flange, a longitudinal groove in each said bottom flange, a plurality of cups imbedded in the top of the pit side walls, a ball bearing journalably mounted in each said cup and adapted to engage in a said groove to facilitate and guide sliding movements of the cover, a reversible electric motor for opening and closing said cover, connecting valve means for supply water and separate connecting valve means for sewage facilities to said building when the frame is at the top of the pit and also when the frame is at the bottom of the pit, and circuit means to energize said motors for raising and lowering the frame and for opening and closing the cover, said circuit means being effective to raise said frame only when said cover is completely open, and to close said cover only when said frame is at the bottom of the pit.

5. Concealable building construction which includes a walled pit, a horizontal frame mounted in said pit and adapted to support a building, vertical worms on which said frame is supported for up and down movements, driving means for said worms including a reversible electric motor, a sliding cover for said pit, side beams for said cover having each a bottom flange, a longitudinal groove in each said bottom flange, a plurality of cups imbedded in the top of the pit side walls, a ball bearing journalably mounted in each said cup and adapted to engage in a said groove to facilitate and guide sliding movements of the cover, a reversible electric motor for opening and closing said cover, connecting valve means for supply water and separate connecting valve means for sewage facilities to said building when the frame is at the top of the pit and also when the frame is at the bottom of the pit, comprising upper and lower water supply pipes extending into a pit wall, upper and lower waste pipes extending into another pit wall, a box-like unit secured to said frame for association with said waste pipes, another unit for cooperation with the water pipes, a pipe secured in each said unit for cooperation with the associated waste or water pipes, a concave seat in the end of each last said pipe, a tube secured on the end of each waste and each water pipe and projecting into said pit, a piston slidably mounted in each tube and having a rounded nose adapted to a said seat, an opening in said nose, a plurality of openings in the base of the piston, a rod projecting from the base of the piston, a circular plate at the end of said rod, an internal annular ring in said tube, a spring to press said plate against said ring, and rounded upper and lower ends on each said unit to cam the associated said pistons into said tubes to disengage said plates from said rings as

the said frame is moved to its upper and lower positions; and circuit means to energize said motors for raising and lowering the frame and for opening and closing the cover, said circuit means being effective to raise said frame only when said cover is completely open, and to close said cover only when said frame is at the bottom of the pit.

6. Concealable building construction which includes a walled pit, a horizontal frame mounted in said pit and adapted to support a building, vertical worms on which said frame is supported for up and down movements, driving means for said worms including a reversible electric motor, a sliding cover for said pit, side beams for said cover having each a bottom flange, a longitudinal groove in each said bottom flange, a plurality of cups imbedded in the top of the pit side walls, a ball bearing journalably mounted in each said cup and adapted to engage in a said groove to facilitate and guide sliding movements of the cover, a reversible electric motor for opening and closing said cover, connecting valve means for supply water and separate connecting valve means for sewage facilities to said building when the frame is at the top of the pit and also when the frame is at the bottom of the pit, comprising upper and lower water supply pipes extending into a pit wall, upper and lower waste pipes extending into another pit wall, a box-like unit secured to said frame for association with said waste pipes, another unit for cooperation with the water pipes, a pipe secured in each said unit for cooperation with the associated waste or water pipes, a concave seat in the end of each last said pipe, a tube secured on the end of each waste and each water pipe and projecting into said pit, a piston slidably mounted in each tube and having a rounded nose adapted to a said seat, an opening in said nose, a plurality of openings in the base of the piston, a rod projecting from the base of the piston, a circular plate at the end of said rod, an internal annular ring in said tube, a spring to press said plate against said ring, and rounded upper and lower ends on each said unit to cam the associated said pistons into said tubes to disengage said plates from said rings as the said frame is moved to its upper and lower positions; and circuit means to energize said motors for raising and lowering the frame and for opening and closing the cover, said circuit means being effective to raise said frame only when said cover is completely open, and to close said cover only when said frame is at the bottom of the pit, and comprising a double pole double throw switch located in the building to energize said motors in reverse directions, normally closed contacts situated to be opened by said frame and said cover as they reach their terminal positions, the opening of said contacts deenergizing the motors, a normally open contact in the cover motor circuit adapted to be closed as said frame reaches its lowest position, and a normally open contact in the frame motor circuit situated to be closed as said cover reaches its fully open position.

7. Concealable building construction which includes a walled pit, a horizontal frame mounted in said pit and adapted to support a building, vertical worms on which said frame is supported for up and down movements, driving means for said worms including a reversible electric motor, a sliding cover for said pit, side beams for said cover having each a bottom flange, a longitudinal groove in each said bottom flange, a plurality of cups imbedded in the top of the pit side walls, a ball bearing journalably mounted in each said cup and adapted to engage in a said groove to facilitate and guide sliding movements of the cover, a reversible electric motor for opening and closing said cover, connecting valve means for supply water and separate connecting valve means for sewage facilities to said building when the frame is at the top of the pit and also when the frame is at the bottom of the pit, and circuit means to energize said motors for raising and lowering the frame and for opening and closing the cover, said circuit means being effective to raise said frame only when said cover is completely open, and to close said cover only when said frame is at the bottom of the pit, and comprising a double pole double throw switch located in the building to energize said motors in reverse directions, normally closed contacts situated to be opened by said frame and said cover as they reach their terminal positions, the opening of said contacts deenergizing the motors, a normally open contact in the cover motor circuit adapted to be closed as said frame reaches its lowest position, and a normally

7

open contact in the frame motor circuit situated to be closed as said cover reaches its fully open position.
